UNITED STATES PATENT OFFICE.

HENRY G. STURGES, OF UTICA, NEW YORK.

FOUR-WAY-STRAP BUCKLE.

1,419,592.

Specification of Letters Patent. Patented June 13, 1922.

Application filed October 5, 1921. Serial No. 505,575.

To all whom it may concern:

Be it known that I, HENRY G. STURGES, a citizen of the United States, residing at Utica, in the county of Oneida and State 5 of New York, have invented a new and useful Improvement in Four-Way-Strap Buckles; and I do hereby declare the following, when taken in connection with the accompanying drawings and the characters 10 of reference marked thereon, to be a full, clear, and exact description of the same, and which said drawings constitute part of this application, and represent, in—

Fig. 1, a plan view of a package showing 15 the application thereto of my improved four-way-strap buckle.

Fig. 2, a detached view of the buckle with the fixed end of the strap broken away.

Fig. 3, an edge view thereof.

Fig. 4, a detached view of the buckle-frame from which the slide has been removed.

My invention relates to an improvement 25 in a four-way-strap buckle of the class used for books, substantially rectangular packages, and bundles of kindred form, the object being to produce a simple and convenient buckle, constructed with particular reference to preventing the shirring or 30 puckering of the strap in making a right angle turn through the buckle, and also avoiding the undue wear of the edges of the strap.

With these ends in view, my invention 35 consists in a four-way-strap buckle having a straight equalizing-bar located at an angle of 45° to both its axes.

My invention further consists in certain 40 details of construction as will be herein- 45 after described and pointed out in the claim.

In carrying out my invention, as herein shown, I employ a one-piece, sheet-metal buckle-frame having a straight equalizing- 45 bar 5 somewhat exceeding in length the width of the strap 6 and located at an angle of 45° to either the longitudinal or trans- 50 verse axes of the frame, which also com- 55 prises complementary slide-bars 7 located opposite each other, a gripping-bar 8, a tie-bar 9 and an intermediate-bar or reinforce 10. All of these bars are straight, but the equalizing-bar is arranged as de-

scribed at an angle of 45° with respect to the axes of the buckle-frame. Upon the 55 slide-bars 7 I mount a sheet-metal slide 11, the ends of which are folded back upon it so as to form tubular sockets or loops 12 embracing the slide-bars 7, upon which it is free to slide toward and away from the 60 gripping-bar 8 of the buckle-frame. The said slide has outwardly projecting teeth which co-act with the said gripping-bar to hold the free end of the strap, as shown in Fig. 1. The fixed end of the strap is folded 65 over the tie-bar 9 and secured thereto by a rivet 13 or equivalent manner.

In the use of my improved, four-way-strap buckle, the strap 6 is passed around the package and then upward through the 70 triangular opening 14 thereof and outward at a right angle and then around the other axis of the package, after which its free end is passed through the rectangular buckle slide-opening 15, in which position it is 75 gripped between the teeth of the slide 11 and the gripping-bar 8. Now, no matter how great the tension employed in tightening the strap by pulling upon its free end, the strap, as it passes over the equalizing- 80 bar 5, will have the strain equalized throughout its entire width, so that it will not pucker in the slightest, whereby the neatness of the package is improved and also by avoiding the puckering or shirring 85 of the strap, the life of the same is pro- 90 longed, inasmuch as the strain is not thrown on its edges but equally diffused throughout its width, all of the lines of strain being rendered parallel by the equalizing-bar.

The bar 10, which divides the interior space of the buckle-frame into the triangular opening 14 and the rectangular opening 15, reinforces the buckle-frame, acts as a stop for the slide 11, and facilitates the 95 threading of the strap 6 through the opening 14 without fouling with the said slide.

I claim:

A four-way-strap buckle having a one- 100 piece buckle-frame, comprising a tie-bar, a gripping-bar, two slide-bars, a straight equalizing-bar extending at an angle of 45° to the tie, gripping and slide-bars, and an intermediate bar or reinforce paralleling the said gripping-bar and dividing the 105 interior space of the buckle-frame into a tri-

angular opening lying adjacent to the equalizing-bar and a rectangular opening lying between said intermediate bar and the gripping-bar; in combination with a buckle-slide mounted at its ends upon the two slide-bars of the buckle, and coacting with the gripping-bar to grip the free end of the strap.

In testimony whereof, I have signed this specification in the presence of two subscribing witnesses.

HENRY G. STURGES.
